[57] CLAIM

The ornamental design for a directional light warning system for vehicles or the like, as shown and described.

DESCRIPTION

FIG. 1 is a top plan view of a directional light warning system for vehicles or the like showing my new design;
FIG. 2 is a front elevational view thereof;
FIG. 3 is a bottom plan view thereof;
FIG. 4 is a rear elevational view thereof;
FIG. 5 is a side elevational view thereof taken from the left side as the device is depicted in FIGS. 1-4; and
FIG. 6 is a side elevational view thereof taken from the opposite side when compared to FIG. 5.

FIG. 5

FIG. 6
